Patented Nov. 4, 1913.

UNITED STATES PATENT OFFICE.

ROSLA W. WELCH, OF BALTIMORE, MARYLAND, ASSIGNOR OF ONE-HALF TO JOHN TOWNSEND BURWELL, OF MILLWOOD, VIRGINIA.

RICE-HULLING MACHINE.

1,077,659.

Specification of Letters Patent.

Patented Nov. 4, 1913.

Application filed November 15, 1912. Serial No. 731,462.

To all whom it may concern:

Be it known that I, ROSIA W. WELCH, a citizen of the United States, residing at Baltimore, in the State of Maryland, have 5 invented certain new and useful Improvements in Rice-Hulling Machines, of which the following is a specification.

This invention relates to a machine for hulling grain, such as rice, oats, and the 10 like.

The object of the invention is to provide a machine of the character named having an upright revolving cylinder and in which the case that encircles the said cylinder has the 15 capability of expansion and contraction, whereby to increase or lessen the annular space between the cylinder and the inclosing case. It is well known that the grains of cereals such as rice, and oats, vary as to 20 size; the produce of one field may be grain of large size and of another field the same kind of grain may be smaller. By providing for slight expansion of the case, the machine may be set to do effective work in re- 25 moving the skin of large grain, and by contracting the case the machine may be set to do effective work for small grain.

The invention is illustrated in the accompanying drawing, in which,—

30 Figure 1, shows an elevation of the machine in which one vertical half of the machine is shown in section, and the other half shows the exterior view. Fig. 2 shows a horizontal section of the machine on the 35 line 2—2 of Fig. 1. Fig. 3 shows in detail piece of inner concave surface of wall, 11, and the bur at the punched holes. Fig. 4 is a detail view of the outside case adjuster.

The frame comprises four posts, 1, held 40 together by bottom cross-bars, 2, and top, 3; a step-bearing, 4, is at the bottom and a bearing, 5, at the top, and a vertical shaft, 6, is revoluble in these bearings. A revoluble cylinder, 7, having a closed top head, 8, and a metal spider bottom, 9, is secured 45 to the shaft, 6, and revolves therewith. The exterior circumferential wall of the cylinder, 7, is covered with sheep-skin having bent wire teeth, 10, of well-known construc- 50 tion similar to the cards used in combing wool and cotton in textile manufacture. These teeth are spring-teeth, and all the teeth point or trend in a direction reverse to the direction which it is intended the cyl-

inder shall revolve, as indicated by darts 55 in Fig. 2.

A cylindric case, 11, incloses the revoluble cylinder, 7, and this case is supported by the frame and does not revolve. The sheet-metal wall, 11, is punched from the outer 60 surface to form numerous holes, 40, and each hole thus made produces a bur 41, see Fig. 3, on the concave inner surface, 12; the bur is something like that on a tin colander.

Between the projecting ends of the wire 65 teeth, 10, on the cylinder, and the concave wall of the case, 11, an annular space, 13, is formed. An important feature of the invention is the provision shown and presently to be described, for expanding and contract- 70 ing the inclosing case, 11, so as to increase or diminish the size of the annular space referred to.

To give the cylindric case the capability of expanding and contracting it is made in 75 several sections which are separated vertically. In the present instance the case is shown made in four sections, *a*, *b*, *c*, *d*. The four sections or segments are separated from each other by a vertical crack or space, 14, 80 and a thin strip, 15, of sheet-metal on the inner walls of the segments overlaps said crack or space; this strip should be securely fastened to one segment only, and should bridge over the said space, 14, and lie close 85 in contact with the inner surface of the next segment but should not be fastened thereto, being free or loose. By this arrangement, which will be readily understood, the spaces, 14, between the segments will be increased 90 when the case is expanded and will be lessened when the case is contracted, but at all times the thin strips, 15, on the inside will close the spaces. Each of the four seg- 95 ments stands on its end the weight thereof being supported on a circular base, 16, and ball-bearings, 17, may be employed to sustain the segments and facilitate the slight movement they make when expanding or contracting.

Horizontal curved bars, 18, connect be- 100 tween the posts, 1, and these bars form a circle outside of the segments; there are curved bars near the bottom and also near the top. Each segment of the case, 11, has 105 two bolts, 19, secured to its outside at both the top and bottom and the bolts project outward radially. The bolts pass freely

through holes in the curved bars, 18, and on the outer side of said curved bars a spiral spring, 20, surrounds the bolt and the spring is compressed between the curved bar and a nut on the bolt. The effect of these springs is to force the segment sections outwardly or to cause the expansion of the inclosing case, 11. This expansion of the case increases the width of the annular space, 13, where the grain is treated.

10 The means for contracting the case comprise two or more steel bands, 21, which surround the four segments like a hoop except that each band has two ends that are unjoined; one of these bands is above the lowermost curved bar, 18, and the other band is below the uppermost curved bar, 18. When the lower and upper bands are both drawn tightly they serve to compress the four segments of the case. In the present instance the bands, 21, when drawn, press not directly against the exterior wall of the segments but, against friction rollers, 22, which are secured on the said walls. To simultaneously tighten both of these bands, 21, a vertical shaft, 23, is mounted in bearings, 24, and, 25, on the frame and outside of the case, 11. This shaft turns only partially backward and forward. A cross-head, 26, seen in Fig. 4 is fixed on the shaft; one of these cross-heads being on a level with the upper band, 21, and the other cross-head on a level with the lower band.

30 One end of the steel band, 21, is secured 35 in a suitable manner to one end of the cross-head, 26, and the other end of the same steel band, 21, is secured to the opposite end of said cross-head. It will be understood that when the vertical shaft, 23, is turned in 40 the direction to tighten the bands, 21, the cross-heads, 26, will effect the tightening by drawing the two ends of both of said bands, and will overcome the effect of the spiral springs, 20, which tend to expand the segments.

45 The vertical shaft, 23, is operated by a hand-lever, 27, which carries a set-screw, 28. A horizontal curved bar extends between two of the posts, 1, and below the lever, and this bar has a curved slot, 30, through which the said set-screw, 28, passes. By swinging the hand lever, 27, either to tighten or loosen the two steel bands, 21, the set-screw will traverse the curved slot, 30, and when the lever has been placed in the desired position the set-screw, 28, may be tightened and will then hold the lever from movement.

50 At the top of the machine case is a hopper, 31, which will deliver the grain so as to admit it down the annular space, 13, while the interior cylinder, 7, is revolving. The action of the spring teeth, 10, which project from the wall of the revoluble cylinder into the annular space, 13, together with the counter 55 action of the burs, 41, on the concave surface

of the case removes the skin from the rice or other grain, and the hulled grain, mixed with the hulls, discharge together from a spout, 32, at the bottom. The hulled grain may then be separated from the loose hulls 70 by another machine.

The numerous holes, 40, in the case serve for the formation of the burs, 41, they provide for the escape of dust, they prevent the case itself from becoming heated, and also 75 avoid heating of the rice grains.

The cylinder, 7, is driven by a belt (not shown) placed over a pulley, 33, fixed on the vertical shaft, 6.

80 From the foregoing description the operation will be readily understood.

While the improved machine has been described as useful for the purpose of hulling or decorticating grain, it is also useful for polishing grain. The only modification that 85 would be required to adapt the machine for either hulling the grain, or for polishing the grain after it has been hulled, is in the character of the exterior rubbing surface on the revoluble cylinder and the interior 90 surface on the case. All the features in the machine that have anything to do with the expansion or contraction of the case, may be used in machines for treating grain otherwise than hulling, and the appended claims 95 are meant to cover same.

Having thus described my invention what I claim and desire to secure by Letters Patent is:

1. In a machine for treating rice, the 100 combination of an upright revoluble cylinder; a cylindric case completely inclosing said cylinder and comprising a plural number of segmental sections separated vertically from each other and standing on their 105 ends and each section free to move outwardly or inwardly to expand and contract the case; springs to cause the segmental sections of the case to move expansively; flexible bands exteriorly surrounding all of said 110 case-sections, one band being around the lower part of the case and another band around the upper part, and means connected with the ends of said band or bands to draw them, and thereby overcome the 115 expansive effect of the said springs and compress the said case-sections.

2. In a machine for treating grain, the combination of an upright revoluble cylinder; a cylindric case completely inclosing said cylinder and comprising a plural number of segmental sections each free to move either outwardly or inwardly to expand or contract the case; means to cause the said 125 segmental sections to move expansively; two flexible bands exteriorly surrounding all of said case-sections—one band being at the lower part and the other band at the upper part; a shaft outside of the case and parallel with the axis of said revoluble cylinder and 130

capable of turning, and two cross-heads fixed on said shaft—one of which is secured to the ends of one of said flexible bands, and the other cross-head secured to the ends of 5 the other flexible band, whereby upon turning the said shaft the ends of both flexible bands will be simultaneously drawn and the case sections contracted.

3. In a machine for treating grain, the 10 combination of an upright revoluble cylinder; a cylindric case completely inclosing said cylinder and comprising a plural number of segmental sections each free to move either outwardly or inwardly to expand or 15 contract the case; horizontal curved bars

forming a circle outside of the case-sections; bolts secured to the case-sections and passing freely through said bars; springs on the outer side of the bars and drawing outwardly on said bolts to cause the case-sections to expand; and means to overcome the expansive effect of the springs and contract the said case-sections. 20

In testimony whereof I affix my signature in presence of two witnesses.

ROSLA W. WELCH.
